(57) **CLAIM**

The ornamental design for a round pan, as shown and
described.

DESCRIPTION

FIG. 1 is a perspective view of a round pan in accordance
with the subject disclosure.

FIG. 2 is a front view of the round pan seen in FIG. 1.

FIG. 3 is a rear view of the round pan seen in FIG. 1.

FIG. 4 is a right side view of the round pan seen in FIG. 1.

FIG. 5 is a left side view of the round pan seen in FIG. 1.

FIG. 6 is a top view of the round pan seen in FIG. 1; and,

FIG. 7 is a bottom view of the round pan seen in FIG. 1.

The broken line showings of the round pan are included for
the purpose of illustrating portions of the round pan and
form no part of the claimed design.

1 Claim, 7 Drawing Sheets
